UNITED STATES PATENT OFFICE.

WAYNE S. SEARLES, OF PROVIDENCE, RHODE ISLAND.

BOTTLE-CLOSURE.

1,325,586.

Specification of Letters Patent.

Patented Dec. 23, 1919.

Application filed June 5, 1919. Serial No. 302,016.

To all whom it may concern:

Be it known that I, WAYNE S. SEARLES, a citizen of the United States, residing at Providence, in the county of Providence and State of Rhode Island, have invented certain new and useful Improvements in Bottle-Closures, of which the following is a specification.

My invention relates to bottle closures of

10 the hinged type. The essential objects of my invention are to insure against leakage of the bottle contents; to reduce the number of constituent parts to a minimum; to facilitate assembly; to afford a speedy and efficient locking and unlocking of parts; to prevent deterioration and wear of the constituent elements; to enable speedy filling and emptying; to prevent accidental loss of the stopper

20 and automatic elevation of the same; and to attain these ends in a strong and inexpensive structure.

To the above ends essentially my invention consists in such parts and in such combinations of parts as fall within the scope of the appended claims.

In the accompanying drawings which form a part of this specification,

Figure 1 is a front elevation of my closure applied to a hot water bottle or bag, showing the latter broken away and in section,

Figs. 2, 3, and 4, a side elevation, a rear elevation, and a plan, respectively of the closure.

Fig. 5, a plan of the same with the parts in another operative position,

Fig. 6, a section on line 6—6 of Fig. 5,

Fig. 7, a section of the closure in open

position taken on line 7—7 of Fig. 4,

Fig. 8, a fragmentary section of the same on line 7—7 but viewed in the opposite direction;

Figs. 9, 10, and 11 front, side and rear elevation respectively of the rotary plate of the closure; and

Figs. 12 and 13 plan and side elevations respectively of the spring member.

Like reference characters indicate like parts throughout the views.

My closure is herein shown in connection with a hot water bottle comprising the usual rubber body or bag, 15, neck 16, and filling funnel 17. The closure comprises a tubular sheet metal body or socket 19 provided pref-

erably with external ribs or corrugations 20 to be firmly engaged by the elastic neck 16 with which it may be cemented or vulcanized. The upper part of the body has an enlarged portion 22 whose back is cut away as at 24 to form from the material rearwardly directed lugs or ears 26. The remainder of the material at the top of the portion 22 is turned inwardly peripherally and is cut away to form a recess 28 opposite the cut away portion or recess 24, thus forming two arcuate flanges 30 and 31. The flange 30 is preferably longitudinally inclined downwardly in a rearward direction, and flange 31 is likewise downwardly inclined in the opposite direction, as shown in Figs. 7 and 8, and the rear end of flange 30 and the forward end of flange 31 are in this case downwardly bent to form stop projections 33 and 34 respectively. An internal annular shoulder or seat 36 is integral with the body 19 a short distance below the enlargement 22. The flanges form in conjunction with the wall or enlargement 22 guide channels 37 and 38.

A stopper is provided comprising a central cover plate 40 provided with a rearwardly directed extension or neck 41 having lateral pivots or trunnions 43 slideable in vertical guide slots 45 in the ears 26 as shown in Fig. 2. In this instance the material of the extension 41 at the rear of the pivots 43 is rolled over to form a cylindrical shield or housing 47 for a helical spring 48 whose ends 49 engage the portion 41 of the extension, and an intermediate tongue 50 of which engages the body 19. Integral with the under surface of the plate 40 concentrically therewith is a flaring stud 52 which extends through an opening 54 in a disk 55 of rubber or other compressible or elastic material, and which retains the latter by an inclined peripheral portion 56. Concentric with the upper face of the plate 40 and integral therewith is a pivot pin 58 having a conical head portion 59. The pin is loose in a central opening 60 in a rotary plate 62 having an integral yoke handle 64. The peripheries of the plates 40 and 62 are coincident, and the latter is rotatable by the handle 64 relatively to the former. At diametrically opposite points upon the periphery of the plate 62 are front and rear projecting tongues or lugs 66 and 67 with inclined

upper faces 68 and 69 respectively. These cam lugs are disposed at right angles to the handle 64.

In closing, the stopper, which is normally elevated by the spring 48, descends and the cam tongues 66 and 67 pass through the cavities 28 and 24 respectively. The handle 64 is then turned in the direction of the hands of a clock as shown in Fig. 5. During this partial rotation the members 66 and 67 move in the channels 37 and 38 with their cam faces in engagement with the inclined faces of the flanges 30 and 31 thereby pressing the lower portion 55 of the stopper 15 into tight contact with the seat 36. The stops 33 and 34 prevent accidental movement of the cam members in an opposite direction. It will be noted that there is no rotation of the disk 55 during this closure 20 period, but that it moves in a vertical direction only; and that by virtue of the vertical play of the trunnions in the guide slots 45 the stopper is insured a free, straight, and uncramped descent upon the seat 36. As 25 the disk 55 is forced against its seat 36 the former laterally expands into tight engagement with the wall of the socket. Because 30 of the nonrotary descent of the member 55 there is no abrasion, wear, and disintegration 35 effects thereof, particularly after aging. For both these reasons all leakage is insured against. In practice a slight turn 40 only of the rotary plate 62 is sufficient to lock or release the cover which makes prolonged manual turning of a screw member 45 unnecessary. The spring 48 insures the automatic elevation of the stopper without 50 the aid of the operator's fingers. The bottle 55 works may be both filled and emptied speedily and 55 without obstruction; and the remote position of the elevated stopper prevents it from becoming heated when hot water is introduced. The connection of the stopper with the socket insures against loss. Assemblage 60 is facilitated by compressing the lugs 26 over the pivot members 43. One advantage of this is that the socket may be first vulcanized or cemented in the rubber bottle neck, and 65 thereafter the stopper may be attached to the socket, so that the stopper has not been subjected to the defacing effect of the vulcanizing fumes. The integral character of the constituent parts of my novel structure 70 reduce their number to a minimum.

It is to be understood that details of the construction may be varied. I have shown but one, and that a preferred, embodiment of my invention, and I do not purpose limiting the patent granted on this application 75 otherwise than necessitated by the prior art.

I claim:

1. In a bottle closure, a socket, flanges upon the socket, a closure plate pivotally mounted on the socket, a pivot pin in the 85 closure plate, a plate rotatably mounted on

the pivot pin, a handle on the rotatable plate, and lugs on the rotatable plate adapted to engage the flanges.

2. In a bottle closure, a socket, flanges on the socket, a closure plate pivotally mounted 70 on the socket, a locking plate rotatably mounted on the closure plate, lugs on the locking plate engageable with the flanges, a handle on the locking plate, a stud on the bottom of the closure plate, and a disk on the closure plate engaging the stud. 75

3. In a bottle closure, a socket, longitudinally inclined flanges upon the socket, stops on the ends of the flanges, a closure plate pivotally mounted on the socket, a plate 80 rotatably mounted on the closure plate, and lugs on the rotatable plate adapted to slidably engage the flanges.

4. In a bottle closure, a socket, a closure plate pivotally mounted on the socket, a locking plate rotatably mounted on the closure plate, a flaring stud on the closure plate, and a disk embracing the stud. 85

5. In a bottle closure, a socket, a flat closure plate pivotally mounted on the socket, 90 a flat locking plate rotatably mounted on the closure plate, a handle integral with the locking plate and disposed at right angles to the locking plate, and a bearing disk upon the bottom of the closure plate. 95

6. In a bottle closure, the combination of a socket, inwardly directed peripheral flanges on the socket, ears on the socket provided with oblong guide slots, a pivotal closure plate, pivot members on the plate extending into the slots, a second plate rotatably mounted on the closure plate, lugs on the rotatable plate engaging the flanges, and resilient means for actuating the closure plate. 100

7. In a bottle closure, the combination with a socket comprising a body and an annular seat within the body, of flanges on the socket above the seat, a closure plate pivotally mounted on the body and vertically 110 slidably therein, a plate rotatably mounted on the closure plate, lugs on the rotatable plate engageable with the flanges, and a resilient disk upon the closure plate engageable with the seat. 115

8. In a bottle closure, a socket, a closure plate pivotally mounted on the socket, a rotary locking plate on the closure plate adapted to engage the socket, and resilient means for moving the closure plate when the locking plate is rotated. 120

9. In a bottle closure, the combination of a socket, inturned peripheral flanges on the socket, ears on the socket, a closure plate, pivot members on the plate mounted in the ears, a locking plate rotatably mounted on the first plate, lugs on the locking plate movable under and from the flanges, and a spring engaging the socket and closure plate. 125

10. In a bottle closure, the combination of 130

a socket, inturned flanges on the socket, ears on the socket, a closure plate, pivot members on the plate mounted in the ears, a sleeve on the plate between the pivot members, a 5 spring in the sleeve engaging the plate and socket, a locking plate pivotally mounted on the closure plate, and lugs on the second plate engageable with the flanges.

11. In a bottle closure, the combination of 10 a socket, flanges upon the socket, guide ears on the socket, a closure plate mounted in the lugs, a pin on the top of the plate, a locking plate loose on the pin, a handle on the locking plate, cam lugs on the locking plate engageable with the flanges, a stud on the bot- 15

tom of the closure plate, and a disk on the bottom of the closure plate engaged by the stud.

12. In a bottle closure, the combination with a socket, of a closure plate pivotally 20 mounted thereon, a pin integral with the top of the plate, a locking plate rotatably mounted upon the pin, a handle integral with the locking plate, a flaring stud integral with the bottom of the closure plate, 25 and a bearing disk embracing the stud.

In testimony whereof I have affixed my signature.

WAYNE S. SEARLES.
